148,188

DESIGN FOR A PORTABLE BAR

Herbert F. Robert, Malden, Mass.

Application June 26, 1946, Serial No. 131,065

Term of patent 14 years

(Cl. D33—19)

To all whom it may concern:

Be it known that I, Herbert F. Robert, a citizen of the United States, residing at Malden, county of Middlesex, State of Massachusetts, have invented a new, original, and ornamental Design for Portable Bars, of which the following is a specification, reference being had to the accompanying drawing, forming a part thereof.

In the drawings:

Fig. 1 is a perspective view of a portable bar showing my new design and looking at the bar from one side thereof.

Fig. 2 is a perspective view of said portable bar looking from the other side thereof.

I claim:

The ornamental design for a portable bar, as shown.

HERBERT F. ROBERT.
